PERCIVAL B. CROCKER, OF TAUNTON, MASSACHUSETTS, ASSIGNOR TO THE SENTRY COMPANY, OF TAUNTON, MASSACHUSETTS, A CORPORATION OF MASSACHUSETTS

FURNACE WITH DRAIN

Application filed May 15, 1928. Serial No. 277,894.

This invention relates to furnaces of the type wherein material in a suitable container is reduced to a fluid state, and the object is to provide improved means for discharging 5 from the furnace any leakage from the container.

My invention will be well understood from the following description of the illustrative embodiment thereof shown by way of example 10 in the accompanying drawing which shows in side elevation an electrically heated pot furnace with part broken away to disclose the interior.

Referring to the drawing, the form of 15 furnace in which I have shown the principles of my invention embodied by way of example comprises a wall 3 of suitable refractory material defining an interior heating chamber 5 in which may be suspended the container or 20 pot 7 for the material to be heated, the top of this pot being covered in the example shown by the movable cover sections 9. The pot may be heated by means of electric resistance elements 11 disposed adjacent the interior 25 side walls of the chamber. Due to the thickness of the walls 3 and to the material of which they are composed, the outside of the furnace is relatively cool.

In case the pot leaks it is desirable to 30 discharge the leakage from the interior of the furnace, and herein the bottom wall thereof is dished as indicated at 13 so that any liquid material falling into the chamber will gravitate toward a central drain passage 15 opening 35 through the bottom wall of the furnace. It will be understood, however, that the material which is used is not liquid at ordinary temperatures and soon congeals or solidifies. Thus, if an ordinary opening were provided 40 through which the leakage might drip, as it approached the outside of the furnace and a cooler region, the material would solidify and adhere to the wall of the opening and tend to plug the same up. My invention particularly provides for preventing the material from solidifying in the drain passage.

In the form of my invention shown this purpose is attained in two ways; first, by preventing material from making contact with 45 the wall of the passage in the cooler part there-

of adjacent the discharge end, and, second, by minimizing the temperature drop along the wall of the passage. These results are both conveniently obtained by the arrangement shown in which the passage 15 is provided with a metal bushing 17 lining the walls thereof which, being of relatively high heat conductivity, will maintain the discharge end of the passage relatively warm without material loss of heat from the interior of the furnace. Quite apart, however, from heating the wall of the discharge passage in this manner, I preferably provide means whereby contact of the leaking material therewith will be at most accidental, and I have herein shown integrally formed at the upper portion of the bushing 17 a dished drain plate 19 of annular form into which the liquid material is discharged from the sloping surface 13 and having a central opening 21 through which the material falls, this opening 21 being conveniently axially aligned with the bushing 17. The cross-sectional area of the bore of the bushing 17 is considerably greater than that of the opening 21 so that the inner portion 75 of the dished drain plate provides an overhanging lip or flange and liquid material discharged over this flange and dripping over the edge thereof will fall freely through the bore of the bushing away from the walls 80 thereof and, even if congealing while falling, will drop freely in the discharge passage like a drop of rain or a pellet in a shot tower without coming into contact with the wall of such passage in such manner as would permit it to 85 freeze thereon. In case any material should back over and around the edge of the lip under certain conditions of discharge, the relatively high temperature of the bushing 17 at the lower or discharge end thereof due to 90 its good heat conducting qualities will tend to prevent adherence of the solidifying material to the wall in such manner as to obstruct the drain passage.

I am aware that the invention may be embodied in other specific forms without departing from the spirit or essential attributes thereof, and I therefore desire the present embodiment to be considered in all respects as 95 illustrative and not restrictive; reference be- 100

ing had to the appended claims rather than to the foregoing description to indicate the scope of the invention.

Claims:

- 5 1. A furnace of the class described having a heating chamber and a pot suspended therein and spaced from the inner wall thereof, a drain passage through said wall, said wall being shaped to direct thereover leakage from the pot to said drain opening, said passage having a metal bushing provided at its upper end with an inwardly projecting and downwardly sloping flange. 70
- 10 2. A furnace of the class described having a heating chamber and a pot suspended therein and spaced from the inner wall thereof, a drain passage through said wall, said wall being shaped to direct thereover leakage from the pot to said drain opening, said passage having therein remote from its discharge end an overhanging lip to direct such leakage over the edge thereof clear of the wall of the passage. 80
- 15 3. A furnace of the class described having a wall resisting the escape of heat therethrough and defining an interior heating chamber receiving a melting pot in spaced relation to the bottom thereof, the wall at the bottom of said chamber having a drain passage therethrough, said bottom being shaped to direct leakage toward said passage and means to direct such leakage to the central portion of said passage to fall freely therethrough clear of its wall. 85
- 20 4. In a furnace of the class described having a heating chamber and a pot suspended therein in spaced relation to the bottom thereof, a dished drain plate in the bottom of the chamber, said bottom being formed to direct leakage from the pot to said plate, said plate having a centrally located opening and a drain passage through the bottom of the furnace beneath said opening and of greater cross-sectional area. 100
- 25 5. A furnace of the class described having a heating chamber and a pot suspended therein in spaced relation to the bottom thereof, the chamber having a drain passage and the interior wall thereof being shaped to direct leakage from the pot to said passage, said passage having a bushing of thermally conductive material. 105
- 30 6. A furnace of the class described having a heating chamber and a pot suspended therein in spaced relation to the bottom thereof, the chamber having a drain passage and the interior wall thereof being shaped to direct leakage from the pot to said passage, and means whereby heat from said chamber is conducted to the discharge end of said passage to prevent congelation of such leakage therein. 110
- 35 7. A furnace of the class described having a heating chamber and a pot suspended therein in spaced relation to the bottom there- 115

of, the chamber having a drain passage and the interior wall thereof being shaped to direct leakage from the pot to said passage, and means providing for localized heating of the drain passage to prevent congelation of such leakage therein. 120

In testimony whereof, I have signed my name to this specification.
